UNITED STATES PATENT OFFICE.

THOMAS FRANCIS CANNING AND RICHARD GEORGE CLARK, OF SOUTHEND-ON-SEA,
ENGLAND.

MACHINE FOR CHARGING AND DISCHARGING GAS RETORTS.

Application filed August 3, 1925. Serial No. 47,934.

To all whom it may concern:

Be it known that we, THOMAS FRANCIS CANNING and RICHARD GEORGE CLARK, both British subjects, respectively residing at "Sunray," 43 Avenue Road, Southend-on-Sea, and "Manaton," Cheltenham Road, Southend-on-Sea, in the county of Essex, England, have invented certain new and useful Improvements in Machines for Charging and Discharging Gas Retorts, of which the following is a specification.

This invention relates to an improved stoking machine which is suitable for use with various kinds of furnaces, retorts and the like, but is particularly designed for charging and discharging retorts at gas works and will be more particularly described with reference thereto.

The invention is illustrated in the preferred embodiment in the accompanying drawings, in which:

Fig. 1 shows the main parts of the machine in side elevation, with the discharging charger partly withdrawn from a retort, the coal alongside the same being omitted.

Fig. 2 shows the same apparatus in the fully withdrawn position.

Fig. 3 shows a detail on a larger scale.

Fig. 4 shows details of a suitable form of drive, and

Fig. 5 shows a form of clutch for controlling the drive.

In the manufacture of coal gas various mechanical means have been adopted whereby the coal is pushed into the retort by a linked bar carrying transverse pushers and usually a front piece or nose. This linked bar is arranged under a coal hopper and the construction is such that when the linked bar is pushed into the retort the front or nose will drive out the coke, after which the pushers will push coal received from the hopper into its place; the device thus acting as a discharging-charger. When the retort is filled the linked bar is drawn back and the pushers, which are usually pivoted plates, will ride over the coal, thus leaving the retort charged with fresh coal.

It has been proposed to mount endless conveyors of different forms on these linked bars and to employ them to carry the coal into the retort by means of an endless chain having arms or pushers on each side, but in

such constructions the chain has been carried in a trough, built up in sections hingedly attached to each other, and the coal has been dropped into the trough and has been pushed along it by the pushers which finally discharge it over the endmost trough in the retort.

Our invention differs from these previous constructions in that the chain we employ and which has side arms or pushers travels over a centrally arranged linked bar on its upper side or edge and on the underside travels on the floor or bottom of the retort thus dispensing with the sectional troughs.

These chains are arranged to be stationary in relation to the linked bars when the retort is being filled but travel in relation to the said bars when they are withdrawn, and the construction is such that when the linked bars are withdrawn the endless conveyors pass out of the coal without, or practically without, disturbing it. A particular advantage of our invention is the rapidity with which a retort can be charged.

These linked bars have been previously made in various forms and have been actuated by means of a flat-sided wheel which is alternately rotated to bring about the pushing and withdrawing actions and on which the linked bar is carried when out of use.

It is desirable to charge the retorts to such a capacity that when the coal expands it will substantially fill the retort, and our invention is designed to do this in a more efficient manner than has hitherto been possible.

In practice the linked bar is pushed into the retort and the pushers which are then stationary in relation to the bar convey the coal from the mouth of the hopper into the retort. When the full charge of coal is in place the linked bar is withdrawn and the chain or cable is held on its under side, say near the mouth of the retort, with the result that the inner part (that is, the part furthest in the retort) of the endless chain or rope will move from under the bar over its end and back along the top whilst the outer part will have reverse movement. The pushers on the chain or cable will rise almost vertically from under the bar at its inner end and will not appreciably disturb the coal.

We prefer to make the links of substantially elongated D or lozenge shape to facilitate their fitting with the chain or cable round the wheel, or they may be pivoted to each other vertically so as to fit to a flat-sided wheel on a vertical axis.

From this description it will be seen that the coal is carried into the retort by the extending bars or plates on the endless chain or cable which travels inwardly en bloc with the linked bar and at the same speed, but when the linked bar is withdrawn the chain or equivalent with its bars or plates has relative movement with the linked bar.

15 The chain or cable may rest on the bottom of the retort and act as a rubbing strip for the linked bar. The endless chain or cable may be driven for the purpose of withdrawing the linked bar.

20 We will now describe our invention with reference to the accompanying drawings in which one form is shown mainly in diagrammatic manner.

25 Fig. 1 shows the main parts of the machine in side elevation with the discharging-charger partly withdrawn from a retort, the coal alongside the same being omitted for sake of clearness.

30 Fig. 2 shows the same apparatus in the fully withdrawn position.

Fig. 3 shows a detail on larger scale.

Fig. 4 shows details of a suitable form of drive, and

35 Fig. 5 shows a form of clutch for controlling the drive.

In Figs. 1 and 2 a retort is shown at *a* and a telescopic shoot from a hopper is indicated at *b* with the usual platform under it at *c*.

40 It will be understood that the machine can be raised and lowered and sidewardly moved to and from the mouths of any suitable number of retorts, such being accomplished in substantially known or any convenient manner.

45 The machine comprises a main wheel 1 arranged within a guard or outer track 2 and adapted to carry the discharging-charger which is formed of bar-links 3 pivoted together at 4 and over which an endless chain 5 carrying pusher bars 6 is arranged. The outer end of the linked bar is attached to an arm 7 normally free on the shaft of wheel 1 but capable of being locked thereto if desired. This arm may carry a wheel or roller to facilitate the movement of the chain over that end of the linked bar.

An idle wheel 8 serves to hold the chain down on the linked bar and a toothed wheel 9 serves to drive the chain in relation to the linked bar and is controlled by the clutch shown in Fig. 5. The retort is shown in outline at *a* in Fig. 3 and the linked bar and chain are approximately a section on line 65 3-3 of Fig. 1. In this drawing it will be

seen that the pusher bars on the underside of the linked bar rest on the bottom of the retort and are not a close fit to the sides of the retort and that the plates 10 to which they are fixed form part of the chain and overlap the edges of the linked bar to prevent accidental displacement.

70 In Fig. 4 the same reference numbers are used for like parts as in Figs. 1 and 2 and an additional wheel 11 coaxial with wheel 1 is shown. This wheel is fixed to the shaft of wheel 1 and these two wheels always rotate together, being driven by the usual or by any suitable means. A chain 12 is passed over the wheel 11 and over a sprocket wheel 13 forming part of the dog clutch 14. This clutch comprises an outer member 15 having sliding movement on shaft 16 by lever 17. The inner member of the clutch comprises two sets of jaws 18 and 19 into either of which the member 15 can be engaged with a neutral position between the two. In Fig. 5 the clutch is shown in neutral position, but upon movement of the member 15 into engagement with the jaws 18 or 19 the drive of the sprocket wheel 13 is communicated to the shaft 16 and causes it to drive the wheel 9. This clutch is manually or mechanically operated and the wheel 9 can be rotated at will.

75 It is distinctly advantageous to fully charge the retort and we can effect this by first inserting the discharging-charger as above and then by engaging clutch member 15 with either 18 or 19 we drive the chain 5 inwardly on the underside of the linked bar, thus causing the pushers on this lower side to convey coal into the retort and pile it up therein. When the coal is sufficiently packed the clutch is brought to neutral and the drive of wheel 1 will slowly withdraw the discharging-charger and when a sufficient return movement has been made the clutch is re-operated and the chain only is again driven to cause the pushers to pile up the coal as before. This process is repeated as often as may be desired and by it any desired degree of packing of the coal can be obtained. Conversely a very light charge can be obtained if desired by withdrawing the whole device proportionately faster than the travel of the chain.

100 The holding of the chain on the withdrawal movement may be effected in any convenient manner as by a foot-operated lever adapted to thrust a pin or plunger into the chain on the lower side, or by putting the clutch into its neutral position and applying a band, brake or equivalent to the toothed wheel 9.

105 The conveyor is driven when the bar is stationary by the teeth on the wheel 1 and those on wheel 9 which have through the wheel 11 and chain 12 equal action in opposite directions (the wheel 1 on the upper side

and the wheel 9 on the under side) on the endless chain 5; the arm 7 being in its normal free position.

The linked bar can be withdrawn by operating the endless conveyor through the teeth on the wheel 1 which withdraws the conveyor on its upper side whilst the lower side is held at wheel 9, by its brake, or it may be the pin or plunger, with the result that 10 the chain on the upper side travels rearwardly and takes the linked bar back with it, the arm 7 being free at the time.

Assuming a charge of coke is in the retort, the operation is substantially as follows: The 15 discharging-charger is thrust inwardly and its forward end will push out the coke whilst a fresh charge of coal is introduced. If the retort is tightly charged with coke the arm 7 can be clutched to its shaft and will then 20 exert a thrust on the outer end of the linked bar and efficiently push the coke out.

Simultaneously with the discharge of the coke the retort is recharged with coal to a usual degree, but the coal may be more or 25 less tightly packed in either of the manners above described.

We have described the apparatus constructed as a discharging-charger for use in "through" retorts, but it may be used as a 30 charger only when the retorts are of the stop-end kind and with which any suitable means for emptying may be employed.

By the use of a suitable clutch and driving gear the chain or like flexible pusher-carrier 35 can be driven in either direction whilst the linked bar is either stationary or moving and the direction of rotation can be reversed as and when may be desired.

For the purpose of discharging coke from 40 retorts, more particularly stop end retorts, the device is introduced into the outer end of the retort and slowly moved therein with the underside of the chain or equivalent which carries the pushers running in an outward direction and so that the pushers will bite into the coke and draw it outwardly along the bottom of the retort and discharge it at the mouth.

What we claim is:

50 1. A machine for discharging and charging retorts and the like, comprising a linked bar, an endless chain mounted lengthwise

over the linked bar, means for operating the bar, and means for independently operating the chain relative to the bar. 55

2. A machine for discharging and charging retorts comprising a linked bar, an endless chain mounted lengthwise over the linked bar, a wheel for winding and unwinding the bar with the chain, pusher arms extending sidewardly from both sides of the chain and means for driving the chain along the bar. 60

3. A machine for discharging and charging retorts comprising a linked bar, an endless chain mounted lengthwise over the linked bar, a wheel for winding and unwinding the bar with the chain, pusher arms extending sidewardly from both sides of the chain and means for holding the chain on 70 one side of the bar when the bar is being wound or unwound on the wheel. 65

4. A machine for charging gas retorts comprising a linked bar carrying an endless chain having sidewardly extending arms, a wheel on which the bar with the chain can be wound and unwound, gear for driving the chain in relation to the bar, and means for holding the chain on one side of the bar whilst the bar is wound and unwound on the 80 wheel. 75

5. A machine according to claim 1, means for simultaneously moving the bar lengthwise with the chain into and out of the retort, and means to permit the chain to move independently of the movement of the bar. 85

6. A machine according to claim 1, including means to hold the chain stationary with relation to the bar at will. 90

7. A machine according to claim 1, including a clutch for controlling the movements of the link bar and chain. 95

8. In a machine for charging or discharging retorts and the like, a bar made up of a series of pivoted rigid members, an endless chain adapted for travel lengthwise the bar above and below the same, pushers carried by the chain, and means whereby the chain and bar may be moved together or the chain permitted to move relative to the bar. 100

In testimony whereof we affix our signatures.

THOMAS FRANCIS CANNING.
